UNITED STATES PATENT OFFICE.

WALTER B. STEVENS, OF ST. LOUIS, MISSOURI, ASSIGNOR TO LOUISIANA PURCHASE EXPOSITION COMPANY, A CORPORATION OF MISSOURI.

DESIGN FOR A FLAG OR BANNER.

SPECIFICATION forming part of Design No. 36,273, dated April 7, 1903.

Application filed February 14, 1903. Serial No. 143,457. Term of patent 3½ years.

To all whom it may concern:

Be it known that I, WALTER B. STEVENS, a citizen of the United States, residing at the city of St. Louis, State of Missouri, have invented a new, original, and ornamental Design for a Flag or Banner, of which the following is a specification, reference being had to the accompanying drawing, forming a part hereof.

10 This invention relates to a certain new and original design for flags or banners; and it consists in peculiar features and characteristics hereinafter described.

15 The accompanying drawing illustrates an elevation of the design as a flag or banner.

As shown in said drawing, the design consists of a field which is the full width of the flag and about one-third of its length. This

field bears a fleur-de-lis centrally arranged, which is surrounded by an elliptical figure 20 formed of stars. The remaining portion of the flag is divided into three equal horizontal stripes of a contrasting color.

Having thus described my invention, what I claim as new, and desire to secure by Letters 25 Patent, is—

The ornamental design for a flag or banner as herein shown and described.

In testimony whereof I have signed my name to this specification in the presence of 30 two subscribing witnesses.

WALTER B. STEVENS.

Witnesses:

BISSELL WARE,
N. S. BRACON.
